PICKER STICK BUFFER FOR LOOMS
 John G. Williamson, Jr., Charlotte, N.C., assignor to
 Perfecting Service Company, Charlotte, N.C., a cor-
 poration of North Carolina
 Filed Aug. 15, 1960, Ser. No. 49,556
 7 Claims. (Cl. 139—166)

This invention relates to looms, and more especially, to an improved picker stick buffer therefor.

Various types of picker stick buffers have been developed heretofore for yieldably bringing the picker stick and pick shaft to a stop at the end of each active stroke of the picker stick. It has been found that most desirable buffering action may be obtained by using pliable strap members for this purpose. However, in order to provide adequate cushioning or buffering action, such prior devices have had to utilize pliable straps formed of many layers of pliable material or they have had to be excessively thick, and thus have been an expensive part of a loom. Further, such prior buffer straps have been subjected to excessive bending stresses which would not only result in the straps becoming excessively worn or cracked within a relatively short period of use, but the yieldability thereof would decrease from the time the picker stick engaged the same until the picker stick was stopped in the course of each active stroke thereof.

It is an object of this invention to provide an improved picker stick buffer including a support for the buffer strap, which support is so formed that those portions of the strap which are laterally opposed with respect to the path of travel of the picker stick are bowed generally toward the picker stick so that the laterally opposed loop portions of the strap are caused to bend about a relatively large radius upon impact of the picker stick thereagainst as compared to straps supported according to prior known devices. By causing the strap to react in this manner, the resistance of the strap to the movement of the picker stick gradually increases during the buffering action, as opposed to the resistance effected by buffering straps of prior buffering devices.

It is a more specific object of this invention to provide a picker stick buffer of the character described wherein the support for the buffer strap comprises a body having a relatively broad flat surface against which corresponding inner end portions of the strap are clampingly secured and wherein opposed ends of the body are provided with outwardly projecting ribs thereon which engage laterally opposed portions of the strap at the points at which the strap bends away from the substantially flat face of the body. Thus, the opposed ribs maintain the strap in a more elliptical shape from the time of engagement thereof by the picker stick until the picker stick has stopped its movement, as compared to the buffer straps of prior known devices.

It is another object of this invention to provide a picker stick buffer of the character described wherein said substantially flat outer face of the support is provided with serrations thereon to assist in maintaining the strap in the desired clamped position.

Some of the objects of the invention having been stated, other objects will appear as the description proceeds, when taken in connection with the accompanying drawings, in which—

FIGURE 1 is a somewhat schematic front elevation of a portion of a loom frame showing the improved picker stick buffer mounted thereon and showing its relationship to the picker stick while the picker stick occupies an outward position relative to the lay;

FIGURE 2 is a view similar to FIGURE 1 showing

2

the picker stick at the end of an active shuttle-throwing stroke thereof;

FIGURE 3 is an exploded isometric view of the improved picked stick buffer removed from the loom, with parts broken away for purposes of clarity;

FIGURE 4 is a sectional plan view of the improved picker stick buffer taken substantially along line 4—4 in FIGURE 1;

FIGURE 5 is a sectional plan view similar to FIGURE 4, but showing a prior art type of picker stick buffer for purposes of comparison with the picker stick buffer of the present invention.

Referring more specifically to the drawing, the improved picker stick buffer, broadly designated at 10, is mounted on a bracket 11 suitably attached to or integral with the frame 12 of the loom, only one side of a portion of the loom being shown in FIGURES 1 and 2. The lower end of a picker stick 13 is mounted on the lower portion of the loom in a manner well known in the art, and the picker stick 13 is moved inwardly in an active stroke by a lug strap 14 through which a medial portion of picker stick 13 loosely extends. The upper portion of picker stick 13 extends through the usual slot provided in an oscillatable lay 15 and has a picker 16 mounted on the upper end thereof for engagement with a shuttle 17. With the exception of the improved picker stick buffer 10, the parts of the loom heretofore described are conventional and their operation is well known in the art. Accordingly, a further detailed description of the loom 30 is deemed unnecessary.

The improved picker stick buffer comprises a looped buffer strap 20 of pliable or yieldable material, and which may be made from one or more plies of leather, fabric, natural or synthetic rubber, or other suitable pliable web material. Strap 20 is shown as being double-ended, but may be in the form of an endless strap, if desired. The buffer strap 20 is clampingly attached to the loom by a support 21, a clamping plate 22 and a screw 23.

Screw 23 loosely penetrates clamping plate 22 and support 21 and may be threaded into bracket 11 or may have a nut 24 mounted thereon as shown in FIGURE 4. The proximal faces 25, 26 of support 21 and clamping plate 22 are substantially flat or planar and are preferably provided with respective substantially vertical serrations which engage opposed surfaces of the inner portion or proximal ends of the strap 20 to assist in maintaining strap 20 in lateral position with respect to picker stick 13 when the strap is clamped between the proximal surfaces 25, 26 of support 21 and clamping plate 22.

In order to further assist in maintaining the buffer strap 20 in lateral position relative to the picker stick 13, the upper and lower portions of support 25 are preferably provided with respective horizontal outwardly projecting ribs 30, 31 whose proximal surfaces are spaced apart a distance substantially equal to the width or vertical height of the inner portion or opposed end portions of buffer strap 20.

It has been found that, in order that the strap 20 has an efficient buffering or cushioning action and relatively long useful life, it is necessary that the strap is normally maintained substantially elliptically shaped with its longitudinal axis A (FIGURE 4) substantially positioned in alignment with and parallel to the path of movement of the picker stick 13, and with its lateral axis B extending in a horizontal plane at a substantially right angle to the path of travel of picker stick 13, while maintaining the laterally opposed side portions of the buffer strap 20 (in alignment with the lateral axis B thereof) sufficiently outwardly bowed or outwardly convex to insure that said opposed side portions of the buffer strap 20 will spread apart upon impact of the picker stick 13 against the end

portion of the check strap loop opposite from the support 21. On the other hand, it is desirable that the curvature of laterally opposed side portions of the buffer strap defined by the lateral axis B normally have larger radii than the radius of that portion of the buffer strap which is to be engaged by the picker stick 13.

By maintaining such normal configuration of the buffer strap 20, the amount of resistance to movement of the picker stick 13, from the instant it engages the outer surface of the buffer strap 20 until it comes to rest, remains substantially constant or is gradually increased to an extent depending upon the characteristics of the material of which the buffer strap 20 is made.

Now, in order to maintain the desired normal configuration of the buffer strap 20 when it is not engaged by the picker stick 13, opposed sides of the support 21 are provided with outwardly projecting abutments 32, 33 which project in substantially right-angular relation from the main planar face 25 a distance substantially equal to the thickness of the buffer strap 20. Abutments 32, 33 may be in the form of ribs which are preferably rounded, as shown, and which are spaced from respective side edges of the clamping plate 22 sufficiently so as to upset and thereby produce a relatively sharp bend in the buffer strap, as at 34, and to thereby apply laterally inward pressure to opposed side portions of buffer strap 20 and to force outwardly the opposed side portions of strap 20 generally parallel to the path of the picker stick 13. It has been found desirable to space the proximal surface of each abutment 32, 33 from the respective side edge of clamping plate 22 a distance substantially equal to the thickness of the buffer strap 20.

This causes the buffer strap 20 to normally occupy the normal configuration above set forth. Thus, it will be noted in FIGURE 4 that, as picker stick 13 moves inwardly in engagement with buffer strap 20 toward clamping plate 22, the pressure exerted against opposed side portions of the buffer strap 20 by the abutments 32, 33 yieldably opposes lateral outward movement of opposed side portions of buffer strap 20, with the result that, as 40 picker stick 13 moves to the broken line position of FIGURE 4, or from the position of FIGURE 1 to that of FIGURE 2, the gradually reducing radii of opposed side portions of buffer strap 20 yieldably resists inward movement of the outer central portion of the buffer strap 20, thus, bringing the picker stick 13 to a smooth stop without subjecting the picker stick to a sudden shock.

By way of comparison, a prior art type of picker stick buffer is shown in FIGURE 5, wherein those parts which correspond to the parts of FIGURE 4 shall bear the same reference characters with the prime notation added. In FIGURE 5, it will be noted that the support 21' is devoid of any means whatsoever for applying pressure to opposed side portions of the buffer strap 20'. According to, the buffer strap 20' normally occupies a position such that opposed side portions thereof are bowed outwardly and are more acutely curved than the portion of the strap which is engaged by the picker stick 13'.

Accordingly, as the picker stick 13' moves into engagement with the outer surface of strap 20' and subsequently moves the outer portion of buffer strap 20' inwardly to substantially the broken line position of FIGURE 5, it will be noted that opposed side portions of the buffer strap are curved quite sharply as compared to opposed side portions of the buffer strap 20 of FIGURE 4, so that the outer surface of the buffer strap 20' becomes cracked and worn quite easily, and there is very little resistance to the inward movement of the picker stick 13' as it engages the very nearly flat central portion of the buffer strap 20'. It will be noted that the picker stick 13' bows the outer portion of the buffer strap 20' inwardly to a considerably greater extent than the extent to which the buffer strap 20 of FIGURE 4 is bowed inwardly by the picker stick 13 when both of the picker sticks 13, 13'

engage the outer portions of the respective buffer straps 20, 20' under substantially the same amount of force.

From the foregoing, it is apparent that applicant's novel mounting for the buffer strap 20 will maintain greater potential resistance to inward movement of the outer portion of the buffer strap 20 than the support 21' will maintain in the outer portion of the buffer strap 20'. Further, since the abutments 32, 33 maintain a greater strength in the outer portion of the loop of the buffer strap 20, it follows that the abutments 32, 33 of FIGURE 4 also maintain the opposed side portions of the loop formed of buffer strap 20 at larger radii than the opposed side portions of the buffer strap 20' in FIGURE 5, with the result that the buffer strap 20 will have a much longer useful life than the buffer strap 20', assuming that the buffer straps 20, 20' are made of substantially the same material and are of substantially the same width and thickness.

In the drawings and specification there has been set forth a preferred embodiment of the invention and, although specific terms are employed, they are used in a generic and descriptive sense only and not for purposes of limitation, the scope of the invention being defined in the claims.

I claim:

1. A buffer for stopping inward movement of a picker stick of a loom, comprising a rigid support having a substantially planar surface facing the picker stick, a buffer strap in loop form having a portion attached to and extending throughout substantially the length of said planar surface and laterally of the path of the picker stick, abutment means projecting outwardly from laterally opposed ends of said surface and toward the picker stick, and said abutment means engaging outer surfaces of opposed side portions of said loop and serving to upset respective portions of the strap engaged thereby to maintain laterally opposed side portions of the loop at a predetermined curvature.

2. In a loom having a picker stick, and means for imparting active inward strokes to the picker stick; the combination of a buffer for the impact of the picker stick at the end of each active stroke thereof comprising a looped buffer strap, a support having a laterally extending planar surface positioned inwardly of said picker stick, means securing an inner portion of said strap along said planar surface, and spaced means carried by said support and applying pressure to spaced side portions of the strap at its outer surface and adjacent laterally opposed ends of said planar surface in such a manner as to normally maintain said strap in a substantially elliptical shape with its longitudinal axis extending substantially parallel with the path of travel of the picker stick.

3. The combination with a loom having a picker stick, of a buffer for the impact of the picker stick comprising a rigid support having a substantially planar outer surface extending laterally of the path of the picker stick, a pliable buffer strap in loop form, means clampingly securing a portion of said strap against and along said planar surface, and abutment means carried by said support and projecting outwardly therefrom substantially astraddle the clamping means and producing a sharp bend in the buffer strap at each point at which the buffer strap extends outwardly from said planar surface, said abutment means serving to maintain said loop in elliptical form with its longitudinal axis extending substantially parallel to the path of travel of said picker stick.

4. The combination with a loom having a picker stick, of a buffer for the impact of the picker stick comprising a rigid support having a first substantially planar outer surface extending laterally of the path of the picker stick, a clamping plate having a second planar surface of a length substantially the same as the length of said first-named planar surface, a pliable buffer strap in loop form having a portion positioned between the first and second

planar surfaces, means clampingly securing the clamping plate and the buffer strap to said support, and abutment means carried by said support and projecting outwardly therefrom substantially astraddle the clamping plate and producing a sharp bend in the buffer strap at each point at which the buffer strap extends outwardly from the first planar surface, said abutment means serving to maintain laterally opposed side portions of the loop at a substantially larger curvature than that portion of the loop remote from said support

5. A structure according to claim 4 wherein said abutment means comprises a pair of ribs extending substantially vertically along laterally opposed side edges of said support and engaging the outer surfaces of laterally opposed side portions of said strap.

6. A buffer for stopping inward movement of a picker stick of a loom, comprising a rigid support having a substantially planar surface facing the picker stick, a buffer strap in loop form having a portion extending throughout substantially the length of said planar surface and laterally of the path of the picker stick, a clamping plate secured to said support and clamping said portion of the strap to said planar surface, abutment means projecting outwardly from laterally opposed side edges of said support and toward the picker stick, said abutment means being spaced astraddle said plate sufficiently to accom-

modate the strap between the abutment means and opposed side edges of said clamping plate, and said abutment means engaging the outer surface of said strap so as to upset respective portions of the strap engaged thereby and to maintain opposed side portions of the loop at a predetermined curvature.

7. For use in supporting a buffer strap for cushioning the impact of a picker stick of a loom; a rigid support having a planar surface for receiving a portion of the strap thereagainst, abutment means on said support projecting outwardly from opposed ends of said planar surface in substantially right-angular relation thereto, a clamping plate adapted to be secured in fixed relation to said planar surface and also being adapted to engage the surface of said strap opposite from the surface thereof received against said planar surface, and said plate having opposed end edges which are spaced apart a distance substantially equal to the distance between said abutment means.
